UNITED STATES PATENT OFFICE

ALLAN S. BANNISTER, OF PROVIDENCE, RHODE ISLAND, ASSIGNOR TO REVERE RUBBER COMPANY, OF PROVIDENCE, RHODE ISLAND, A CORPORATION OF RHODE ISLAND

DESIGN FOR A SHOE SOLE

Application filed December 3, 1929. Serial No. 33,629. Term of patent 14 years.

To all whom it may concern:

Be it known that I, ALLAN S. BANNISTER, a citizen of the United States, residing at Providence, county of Providence, State of Rhode Island, have invented a new, original, and ornamental Design for a Shoe Sole, of which the following is a specification, reference being had to the accompanying drawing, forming part thereof, wherein:

I claim:

The ornamental design for a shoe sole as shown.

Signed at Providence, county of Providence, State of Rhode Island, this 22 day of November, 1929.

ALLAN S. BANNISTER.
